UNITED STATES PATENT OFFICE.

MARTIN MELIA, OF PHILADELPHIA, PENNSYLVANIA, ASSIGNOR TO COMMERCIAL TRUCK COMPANY OF AMERICA, OF PHILADELPHIA, PENNSYLVANIA, A CORPORATION OF PENNSYLVANIA.

BATTERY-ELEMENT PULLER.

1,239,420.

Specification of Letters Patent.

Patented Sept. 4, 1917.

Application filed November 14, 1913. Serial No. 801,052.

To all whom it may concern:

Be it known that I, MARTIN MELIA, a citizen of the United States, residing in Philadelphia, Pennsylvania, have invented certain Improvements in Battery-Element Pullers, of which the following is a specification.

One object of my invention is to provide a relatively simple and conveniently operative device for forcibly removing the plates or elements of storage batteries from their containing jars in case they should become jammed by reason of warping or swelling, the arrangement of parts being such that there is but little danger, under operating conditions, of injuring either the jar or the elements.

Another object of the invention is to provide a device of the general character above noted which shall include novel means for engaging the elements of a storage battery cell and other means for engaging and holding the jar or container in which the elements are mounted, whereby it shall be possible to conveniently and quickly remove the elements from the jar even though these may have been so swelled or otherwise distorted as to strongly grip the walls of the latter.

These objects and other advantageous ends I secure as hereinafter set forth, reference being had to the accompanying drawings, in which:—

Figure 1 is a side elevation, partly in vertical section, illustrating one form of my invention;

Fig. 2 is an end elevation of the device shown in Fig. 1, and

Figs. 3 and 4 are respectively a plan, partly in vertical section, and a side elevation of a slightly modified form of the invention.

In that form of my invention shown in Figs. 1 and 2, 1 represents an elongated base piece, such as a heavy plank or casting, in which are fixed two similar standards 2 projecting upward at a distance apart slightly greater than the width of the container of the particular storage battery cell on which the apparatus is intended to operate. These standards are preferably braced and have

projecting from the lower parts of their adjacent faces guide pieces 3, whereby the battery jar is approximately centered between them.

Extending across the top edge of each of the standards 2, and suitably fixed thereto is an inwardly extending strip or flange 4 whose adjacent edges are recessed to provide holding shoulders for the reception of the top edge of a battery jar or container 5 in such manner as to prevent its vertical movement from between the standards 2.

For engaging the plates or elements of the battery I provide a handle in the shape of an elongated bar 6 connected by a horizontal bolt 7 to the upper part of a frame 8. This latter consists of two substantially parallel plates 8^a spaced apart by sleeves 9 formed by the rolled up ends of hooks 11 respectively mounted on bolts 10 connecting the lower portions of said plates. These hooks are made of relatively strong plate material whose lower ends are bent away from each other to form plate-engaging portions 12. The outer surfaces of these portions are 75 preferably inclined or slightly curved as shown, and said hooks are at all times pressed apart by a pair of springs 13 respectively confined between them and a central member 14 which extends transversely 80 between the parallel plates 8^a of the frame.

In order to limit the outward movement of the two hooks, I provide for each of them a pin 15 extending between the two plates 8^a so that while free to move toward each other from the positions shown when the springs 13 are compressed, they normally are substantially parallel.

In storage batteries used to furnish current for the propulsion of motor vehicles, it is found that the plates or elements of such batteries frequently swell or warp so that it is extremely difficult to remove them from their jars without breaking the latter, and in applying my invention to such a cell the latter is placed on the base-piece 1 by being moved sidewise between the two standards 2, so that its upper edges rest within or under the shouldered recesses of the flanges 4.

It is to be noted that the members 8^a of

the frame 8, as well as the cross-piece 14, are made of some insulating material such as fiber so that the hooks 11 are electrically insulated from each other. The latter are then lowered or forced down between the two straps 17 and 18 which connect alternate battery elements in the well known manner and to which are connected the terminals 19 and 20. Under these conditions the turned-over portions 12 of the hooks 11 slidably engage the adjacent edges of the straps, thus forcing said hooks to turn on their pivots against the action of the springs 13, until when they have been lowered sufficiently far, they move outwardly into the positions shown in Fig. 1, so that their turned-over portions 12 rest under portions of the connecting straps 17 and 18 respectively. The operator then stands upon the base 1, preferably with his feet respectively adjacent the standards 2 and pulls upwardly on the handle 6. Since the jar or container 5 is held by the flanges 4 from moving vertically out from between the standards 2, the elements 16 of the battery are forcibly removed from said jar.

In cases where the battery elements have become so firmly jammed within the jars or containers as to render it difficult or impossible to remove them by hand with the apparatus shown in Figs. 1 and 2, I may employ the modification of my invention shown in Figs. 3 and 4. In this case the base piece 1^a has fixed to its ends relatively heavy angle pieces 20 and 21 or any other suitable structures projecting substantially at right angles to its general line. The projecting end of the piece 20 is longitudinally slotted for the reception of the threaded end 22 of a bolt, which is pivotally or otherwise mounted on the bolt 7 of the hook-carrying frame 8, whose construction is substantially identical with that shown in Figs. 1 and 2. This bolt may be held in any desired position in its slot by a pair of jam nuts, depending upon the dimensions of the particular batteries on which it is desired to operate.

The second angle member 21 likewise has its projecting end slotted for the reception of a double flanged bearing sleeve 24, through which loosely passes an elongated screw 25, it being noted that said sleeve is rectangular in section so that it cannot turn and is splined to the screw so that this also is held from rotation though free to slide longitudinally through said sleeve. The latter may be clamped in any adjusted position in the slot by a bolt 26 connecting the two branches or side portions of the end of the angle member 21.

Mounted on the screw 25 outside the angle piece 21 is a hand wheel 28 which when rotated in either direction causes a longi-

tudinal movement of said screw. The latter is supported by the sleeve 24 so that it extends in substantially the line of the bolt 22 and its end nearest said bolt is preferably forked as shown at 29, having a pin 30 extending between its branches. In this case the jar-engaging member consists of an elongated plate 31 bent into a U-shaped form and having its extremities turned over to provide hooks 32 for engagement with opposite edges of the battery jar 5. To the center of the base of this member 31 is fixed a suitably formed hook 33 capable of entering between the forks of the end 29 of the screw 25, so as to engage the cross pin 30 thereof. In addition a pair of handles 34 is fixed to the base of this element 31, to facilitate the manipulation thereof.

Mounted on the base structure 1^a adjacent the hooked ends of the element 31 is a U-shaped yoke piece 35 having feet 36 and closely embracing said member; its side elements having longitudinally extending slots for the reception of threaded studs 38 projecting outwardly from the side portions of the member 31 to which they are fixed. Each of these studs has mounted upon it a thumb-screw 39.

In using this form of my apparatus, the member 31 is placed around the jar 5 from which the elements 16 are to be removed, with its hooks 32 engaging two of the opposite top edges thereof. The thumb-screws 39 are then loosened and the yoke 35 is adjusted until it supports the front end of the member 31 at the proper height above the base 1^a, so that its central plane includes the center line of the bolt 22, after which said screws are tightened. The open end of the jar is then advanced toward the hooks 11 whose ends 12, being pressed toward each other by reason of their engagement with the terminals or connecting straps of the battery elements, finally spring outward into the positions shown in Fig. 3 in which they respectively extend under portions of said straps or terminals. The screw 25 is then adjusted so that the pin 30 of its forked end 29 may be caused to enter the recess of the hook 33. Thereafter revolution of the hand wheel 28 causes said screw to be moved longitudinally through the angle member 21 with the result that the battery jar 5 is forcibly drawn away from the battery elements 16.

Obviously the screw 25 and base 1^a may be of suitable proportions to permit of the battery jar being completely drawn off of the battery elements and thereafter the latter may be disengaged from the hooks 11. The forked end of the screw 25 is likewise disengaged from the hook 33 of the member 31 and this is lifted clear of the battery jar.

With this form of my invention, the handles 34 may be employed to draw the member 31 and with it the jaw 5 away from the elements 16 if these latter are not so tightly 5 jammed in the jar as to require the use of the screw. In any case the battery elements may be forcibly removed from a jaw or container within which they are mounted and by the use of the apparatus above described 10 such removal is quickly accomplished without tendency to break or chip the jars.

I claim:

1. The combination in a battery element pulling device of a frame providing two 15 substantially parallel standards; a U-shaped member mounted on one of said standards and having hooked ends adapted to engage the edges of the open end of a battery jar for holding the same against longitudinal 20 movement; and a device mounted on the other standard having transversely extending parts formed to engage the terminal portions of the battery elements in the jar for withdrawing the same while said jar 25 is held by said U-shaped member.

2. The combination in a battery element pulling device of means formed to engage the edges of a battery jar to hold it from longitudinal movement; and means including 30 two members insulated from each other and formed to respectively engage the terminal portions of the two sets of elements for withdrawing the same from the jar while it is so held.

3. The combination in a battery element pulling device of means for holding a battery jar from longitudinal movement; with means including a frame and two hooks mounted thereon for respectively engaging 35 the terminal portions of the elements in the jar for withdrawing the same while said jar is held; with automatic means acting on the hooks to force them apart.

4. The combination in a battery element pulling device of means for holding a battery jar from longitudinal movement; an element withdrawing device consisting of a frame, and two hooked members pivotally mounted on the frame so that their end portions 40 are free to move toward and from each other; and springs tending to cause the hooked ends of said members to move apart.

5. The combination in a battery element pulling device of means for holding a battery jar from longitudinal movement; means for withdrawing the elements from the jar while it is so held, the same including a frame and two members pivoted thereto and having their extremities oppositely hooked; means for insulating said members from each other; means for automatically pressing apart the hooked ends of the members; and means for limiting the movement 50 of said members on their pivots.

6. The combination in a battery element 65 pulling device, of means for holding a battery jar from longitudinal movement; an element removing device consisting of a frame and two hooked members pivoted thereto and having their hooked ends oppositely inclined at an angle to their main portions; with a spring for normally pressing said ends apart.

7. The combination of a supporting frame; a hook device mounted thereon for engaging the elements of a battery cell; a second hook device also mounted on said structure in position for engaging the edges of a battery jar; and mechanism mounted to simultaneously subject both of said devices to tension to withdraw the elements 75 from said jar.

8. The combination of a base; a hook device mounted thereon for holding the elements of a battery cell against longitudinal 85 movement; a second hook device for engaging the jar containing said elements; with mechanism also mounted on the base and detachably connected to said jar-engaging device in position to exert tension on both 90 of said devices in withdrawing the elements from the jar.

9. The combination of a supporting structure having two projecting substantially parallel members; an element-engaging device connected to one of said members; a screw carried by the other member so as to be longitudinally movable therethrough and projecting toward said device; a jar-engaging device detachably connected to 100 said screw; and means for longitudinally moving the screw to separate the jar and the elements therein.

10. The combination of a base; a device mounted thereon and formed to detachably 105 engage the edges of a battery jar to hold it against longitudinal movement; means for supporting said device in operative position on the jar at a predetermined distance from the base; means carried by said base 110 for engaging the elements in the battery jar; and means for forcibly moving the jar-engaging device away from the element-engaging device.

11. The combination of a supporting 115 structure; a device mounted thereon for engaging the elements of a battery cell for holding the same against longitudinal movement; a U-shaped member having hooked extremities formed to engage the edges of 120 the open end of the jar containing said elements; a screw connected to said U-shaped member; and a nut operative on the screw and engaging the supporting structure.

12. The combination of a supporting structure having two projecting members each provided with a slot; an element-en-

gaging device adjustably mounted in the slot of one of the members; a jar engaging device; with mechanism adjustably mounted in the slot of the other member and detachably connected to said jar-engaging device for longitudinally moving the same away from the element-engaging device.

In testimony whereof, I have signed my name to this specification, in the presence of two subscribing witnesses.

MARTIN MELIA.
